CLAIM

The ornamental design for a frame assembly of a patient interface, as shown and described.

DESCRIPTION

FIG. 1 is a front perspective view of a frame assembly of a patient interface;

FIG. 2 is a rear perspective view thereof;

FIG. 3 is a top plan view thereof;

FIG. 4 is a bottom plan view thereof;

FIG. 5 is a left side elevational view thereof, the right side elevational view being a mirror image of FIG. 5;

FIG. 6 is a front elevational view thereof; and,

FIG. 7 is a rear elevational view thereof.

The broken lines in the drawings depict portions of the frame assembly of a patient interface and form no part of the claimed design.
